CASE CONSTRUCTION

George B. Parsons, Sparrow Bush, N.Y., assignor to Skydyne, Inc., Port Jervis, N.Y., a corporation of New York

Filed Sept. 10, 1957, Ser. No. 683,057

2 Claims. (Cl. 220—84)

My invention relates to a case construction and more particularly to a construction for forming a more perfect corner.

In the manufacture of many cases, especially for instruments and other articles, it is essential that a tight case be formed and the case must be of such construction as to withstand rough handling without ensuing leaks or breaks for the entrance of moisture to the inside of the case. Cases are often dropped on the corners and such dropping of a case on the corner often causes the sides or edges adjacent the corner to open up and permit the entrance of moisture. Some cases have been provided with a steel cap to fit three sides of the corner and have been riveted or otherwise secured to the sides. However, that construction is relatively costly and does not always give the desired protection to the case. Using a cap to fit three sides necessitates riveting the cap to the exterior of the case in three planes. Drawing up the rivets in two planes is elementary but unless there is a perfect fit it is difficult to pull up the rivets in the third plane. Also the rivets tend to elongate the holes and cause leakage.

It is an object of my invention to provide an improved corner construction for a case which will be strong, readily assembled, easy to hold in assembled position and easy to seal against the entrance of moisture.

Other objects and various features of novelty and invention will be hereinafter pointed out or will become apparent to those skilled in the art.

Briefly stated, in a preferred form of the invention, I provide corner blocks for the corners of the case, and each corner block has three arms at right angles to each other. The sides of the case at each corner have edge rails cooperating with said arms for holding the rails and sides securely to said corner block. The block is furthermore provided with means for forming a groove for receiving a sealing compound for sealing the corner against the entrance of moisture. The edge rails forming parts of the sides may be in the form of extrusions having channels for receiving the arms and side panels, or they may be in the form of other shapes such as angles arranged for embracing the arms and also for holding the side panels. The corner blocks may be provided with means for assisting in stacking the cases so as to avoid slipping of the stacked cases.

In the drawings which show, for illustrative purposes only, preferred forms of the invention:

Fig. 1 is a more or less schematic view of a case which is shown as completely closed, but it will be understood that the case is so shown only for the sake of illustration and normally a case would have the top portion separate so as to act as a lid;

Fig. 2 is an enlarged horizontal sectional view through the case shown in Fig. 1;

Fig. 3 is an enlarged exploded perspective view of the lower corner of the case shown in Fig. 1;

Fig. 4 is an enlarged perspective view of a corner block, illustrating features of the invention and taken more or less in the plane of the line 4—4 of Fig. 2;

2

Fig. 5 is an enlarged sectional view, taken substantially in the plane of the line 5—5 of Fig. 2;

Fig. 6 is a fragmentary view, showing the corner blocks of two cases, one piled on the other;

Fig. 7 is a view similar to Fig. 3, to illustrate a different type of edge rail;

Fig. 8 is a horizontal sectional view through the construction shown in Fig. 7.

In the form illustrated in Figs. 1 to 6, the eight corners of the box are all duplicates of each other, but it is to be understood that it is not always necessary to make all of the corners duplicates of each other because lids, for example, may be somewhat differently formed. However, in the preferred form shown, all of the corners will be described as being duplicates of each other.

At each corner there is what may be termed a corner block 5 of more or less cubical form, having three arms 6 projecting at right angles to each other. These arms may be formed integrally with the corner block or cast in the block or otherwise formed, but the arms and block should be rigidly secured to each other. The corner block and arms are preferably metal.

The three sides coming together at each corner, for example as shown in Fig. 3, may each consist of an edge rail 7, which has channels 8—9 at right angles to each other for receiving panels 10—11, as will be clear. In the particular form shown in Figs. 1 to 6, these edge rails are in the form of extrusions in which the channels 8—9 are so arranged that one is deeper than the other. The deeper channel in each case is passed over and fits on an arm 6 of the corner block, as is clearly shown in Fig. 3. The deep channels 8 are deep enough so as to receive the arms 6 and also the panels 10 shown in Figs. 2 and 5. The panel 10 is cut away to some extent, as illustrated in Fig. 3, so as to fit down into the channels, except where the arms 6 projects into the channels, but even there the channels are deep enough so that a part of the panel 10 fits in the channels 8. One of the upper side panels 11' is also cut away so as to make way for the upstanding arm 6, but even there part of the panel 11' fits in a vertical channel in the vertical edge rail 7. The other side panel 11 is not cut away since it simply abuts the edge of the upstanding arm 6, or rather the bottom of the shallow channel, as will be clear (Fig. 2).

All of the edge rails extend up all the way to the block and abut the sides of the block. The edge rails may be secured as by riveting directly to the block or to the arms 6, or the edge rails may be riveted or otherwise secured to all of the panels, and the panels thus may serve to hold the three sides, including the edge rails 7, in position against the sides of the block.

The block itself has an upstanding lip 12 on each of the three adjacent sides where the arms 6 are located. This lip 12 defines the outer side of a groove or channel between the sides of the edge rails or extrusions and the lips, and this groove is convenient for holding and protecting sealing compounds 13 shown particularly in Fig. 5. Thus, when the edge rails and the panels are all rigidly secured together with the block, a very strong and tight joint results and the sealing compound may seal all of the spaces or joints between the block and adjacent panels and edge extrusions. This protected groove between the lip 12 and the sides of the extrusions is in excellent position to receive a seal and protect the sealing compound against injury.

In the form shown in Fig. 7, the parts are exactly the same as heretofore described, except that the edge rail 15 instead of being an extrusion is formed of two angles 16—17 parallel to each other and having corresponding legs embracing the arms 6 and having the other corresponding legs spaced apart for receiving the side panel, as heretofore described.

The legs of the angles which embrace the legs 6 are also long enough so as to form a channel for embracing a part of the adjacent side panel designed to fit in such a channel. Here, again, the angles are riveted to the panels and also preferably to the arms 6 so as to provide a perfectly rigid and firm joint between the sides and the edge rails and the corner block itself. Of course, it would be possible to use extrusions, as shown in Fig. 3, for one or more of the adjacent sides and separate angles, as shown in Figs. 7 and 8, for the sides at any particular corner. However, normally the rails are formed as duplicates of each other and are in the form of extrusions or separate angles.

In the preferred form, the corner blocks are so designed as to permit ready stacking of the cases one on the other, so as to prevent slipping of the stacked cases. Thus, as shown in Fig. 6, the top block of one case and the bottom block of the case above it, have coating members for preventing slipping sideways. In the form shown, the top block of the lower case has a depression 18 therein and at the under side of the top block, there is a boss 19 designed to fit in the depression 18 so as to prevent slipping of the cases sideways when they are stacked one on the other.

It will be seen that I have provided a case which will be very strong and rigid. The corners instead of being mitred or abutted, or otherwise secured together in rather unsecure fashion, are all securely held on the arms of a corner block so that there is no danger of having the sides come apart so long as they are secured to the block. No outside steel protecting cover member is required at the corner since the block itself serves for purposes of a steel reinforcing shield often used in cases of the prior art. The case, when once riveted or otherwise secured together, is designed to hold permanently and the sealing compound is definitely held in the groove surrounding the adjacent sides of the block where the sides abut. The cases are arranged for ready and safe stacking.

The cover block is preferably of light metal like an aluminum alloy, and the arms may be integral or separate as described. However, the block and arms are rigid and in effect integral. The edge rails are preferably extrusions of light metal as are the substitute separate channels, when employed. The side panels are preferably sheet metal clad panels of light material such as balsa wood, fibre, or other desired material. The metal covering for the side panels is preferably sheet aluminum or the like.

The corner block is generally superior to a prior art corner including a sheet steel cover for the corner. With the corner block, a case may be dropped and the corner block may become dented or deformed without in any way impairing its usefulness as a means for holding the corner securely.

No reliance need be placed on mitred corners or butt joints, since applicant's corners are otherwise and more securely held than has hitherto been possible by prior art methods.

While the invention has been described in considerable detail and preferred forms illustrated, it is to be understood that changes and modifications may be made within the scope of the invention, as defined in the appended claims.

10 I claim:

15 1. A corner construction for a case having side panels comprising a substantially cubic corner block member, said block member having three of its sides with outer surfaces all at substantially right angles relative to each other, an arm member extending from each of the remaining three sides of said block member so that the three arms extend at substantially right angles relative to each other, three edge rail members each having a first channel receiving both an arm and one edge of a side panel therein and a second channel at a substantially right angle to said first channel receiving one edge of another side panel therein, and a lip formed around the periphery of said outer surfaces of said corner block member to receive a sealing compound.

20 2. A corner construction for a case having side panels, comprising a substantially cubic corner block member, said block member having three of its sides with outer surfaces all at substantially right angles relative to each other, an arm member extending from each of the remaining three sides of said block member so that the three arms extend at substantially right angles relative to each other, edge rail members forming a first channel receiving both an arm and one edge of a side panel therein and a second channel at a substantially right angle to said first channel receiving one edge of another side panel therein, each of said panels being notched to fit over said block member at the corner, and a lip formed around the periphery of said outer surfaces of said corner block member to receive a sealing compound.
